BEACH CHAIR

Frederick H. Lassiter, Charlotte, N. C.

Application September 21, 1934, Serial No. 744,955

2 Claims. (Cl. 155—1)

This invention relates to a chair and more especially to a chair adapted to be used on beaches and has means associated therewith whereby the chair may be closed on all sides to 5 form a dressing compartment.

It is, therefore, an object of this invention to provide a beach chair having a collapsible top pivoted thereto and also an extended support connected to the front side thereof upon which a 10 suitable curtain may be mounted, said support being foldable so as to present no obstruction to the user of the chair when it is desired to be used for seating purposes only.

It is a further object of this invention to provide a beach chair with a removable seat therein and adjustable foot rests associated with said seat to enable the owner of the chair to remove the seat when the seat is not in use, without the necessity of moving the entire chair to prevent 15 unauthorized use.

It is a further object of this invention to provide a chair which comprises a light framework, said framework being normally secured against overturning by wind pressure by means of a suitable weighty substance such as sand and the like which is placed in a container disposed beneath the seat of the chair.

Some of the objects of the invention having been stated, other objects will appear as the description proceeds when taken in connection with the accompanying drawings, in which:—

Figure 1 is a side elevation of the invention as it appears when it is used for a dressing compartment;

Figure 2 is a view looking at the left-hand portion of Figure 1 but showing the curtains removed and also the top in folded position;

Figure 3 is a vertical sectional view taken along line 3—3 in Figure 2 showing the curtain mounted on one of the collapsible supports;

Figure 4 is a sectional plan view taken along line 4—4 in Figure 1;

Figure 5 is a sectional plan view taken along line 5—5 in Figure 1 showing the upper curtain supporting means in extended position;

Figure 6 is an elevation of the central portion of Figure 5 showing the means for connecting the two upper curtain supports when the supports are in an extended position;

Figure 7 is an enlarged view of the right-hand portion of the adjustable foot rest as shown in Figure 3.

Referring more specifically to the drawings, the numerals 10 and 11 denote the side frames for the chair which are connected together by suitable

transverse struts 12, 13, 14, 15 and 16. The side frame 10 is comprised of two vertically disposed posts 17 and 18 which are connected together by suitable longitudinal struts 19, 20, 21 and 22. Likewise, side frame 11 is comprised of two vertically disposed posts 23 and 24 which are secured together by longitudinal struts 25 and 26, 5 27 and 28.

Secured to side frames 10 and 11 and on the same horizontal plane as struts 22 and 28 is a 10 U-shaped member 36 which is adapted to receive the rings 37 on curtains 38 and 38a. The upper end of curtains 38 and 38a have secured thereto suitable rings 39 which rings are supported by L-shaped members 40 and 41. The member 40 15 is slidably mounted in bearings 42 and 43 which are secured to strut 19 of frame 10. An L-shaped member 41 is slidably mounted in similar bearings 44 and 45 which are secured to strut 25 of frame 11.

The ends of the two members 40 and 41 are secured together in a suitable manner as shown in Figure 6, where a collar 51 is threadedly secured on the end of member 41 and has a bore therein in which the free end of member 40 is 20 adapted to fit. A suitable pin 52 is then inserted through the collar 51 and through the end of member 40 to secure the ends of the two members in position when it is desired that the curtain be 25 in an extended position. When it is desired that 30 the chair be used for observation purposes only, to allow the sun to enter the members 40 and 41, are collapsed and will assume a position as shown in Figures 2 and 3.

It is also seen that when the members 40 and 35 41 are in this position that the rods may be moved to the right in a manner as shown in Figure 3 in order that the curtain and supports may not act as an obstruction to one entering the chair.

A suitable collapsible top 54 is provided which is hingedly secured to the top of frames 10 and 11 as at 55 and 56. The top 54 is comprised of a plurality of U-shaped bows 57, 58, 59 and 60 which are held in extended position by collapsible 45 struts 61 and 62. These struts are all identical and are shown in extended position in Figure 1 whereas, struts 62 are shown in folded position in Figure 3. The top is adapted to be covered with a suitable material such as canvas and the 50 like, which will be denoted by the reference character 63. This canvas is secured to transverse struts 19, 15 and 25, so that when the top is in extended position, it will present a uniform appearance.

A removable seat 70 is provided which has a back 71 pivoted thereto as at 71a. The back is maintained in the desired position by any suitable means such as rod 72 which is adapted to engage the racks 73 and 74 in struts 20 and 26, respectively. By placing the rod 72 in different notches in these racks, the angularity of the back may be adjusted. A suitable compartment 75 is disposed beneath the seat 70 which may be used for stowing clothing and the like.

Foot rests 76 and 77 are provided which are identical in all respects and a description of one will be made and like reference characters will apply to similar parts on the other foot rest. 15 This foot rest is comprised of portion 78 upon which the feet of the occupant are adapted to rest and a portion 79 which extends through the partition 80. A suitable bracket 81 is secured to the lower side of the partition 82 which forms 20 the lower side of the compartment 75. This bracket 81 has a projection 83 which is adapted to fit into the rack teeth 84 of one of the foot rests 76 or 77.

It is seen that by raising the left-hand end of 25 foot rests 76 or 77 (Figs. 3 and 7), the right-hand end of the foot rests will be disengaged from the projection 83 and the position of the foot rest may be adjusted to suit the user. If desired the foot rest may be pushed entirely to 30 the right, and be placed in a position where it will not obstruct the user's feet, when the chair is being used as a dressing compartment.

A pair of foldable tables 85 and 85a are secured to the members 10 and 11 which are identical in all respects and similar parts will be given like reference characters. The table 85, 35 in Figures 1 and 2, is shown in folded position and connected to frame 10. This table is pivoted to the transverse rod 20 by any suitable means such as hinges 86 and a collapsible brace 40 87 has one end secured to the table 85 and its other end secured to transverse strut 21. In Figures 2 and 3 the table 85a is shown hingedly secured to transverse strut 26, whereas the collapsible brace 87 is shown hingedly secured to 45 the lower side of table 85a and to the transverse strut 27.

Container 88 is secured in the lower side of the beach chair and is supported by transverse members 22 and 28. This container is adapted 50 to contain some suitable weighty material such as sand and the like in order to place added

weight to the chair to secure the same against overturning due to external forces such as wind pressure and the like. The body portion of the chair is adapted to be covered by any suitable light weight covering such as canvas which will 5 be denoted by the reference character 90.

In order to move the chair from place to place, handles 91 and 92 are provided which are secured to transverse members 20 and 26 respectively, of end frames 10 and 11.

The canvas covering may be secured to the framework in any desired manner such as snap fasteners 95 which permit the side coverings to be quickly removed when greater exposure or better observation is desired.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. A beach chair comprising a framework having sides and a back, a seat disposed in the framework, a cover detachably secured over the sides and the back, a plurality of bows forming a top framework, the ends of the bows being pivotally secured at a common point at the top edges of each side, a pair of rods mounted for 30 forward and rearward sliding movement in the top portion of each side portion and being bent so their ends can be joined centrally of the chair to form a curtain support, and a detachable covering for said top.

2. A beach chair comprising a framework having sides and a back, a seat disposed in the framework, a cover detachably secured over the sides and back, a plurality of bows forming a top framework, the ends of the bows being pivotally secured at a common point at the top edges of each side, a detachable covering for the top, a pair of rods mounted for forward and rearward sliding movement in the top portion of each side portion and being bent so their ends 40 can be joined centrally of the chair to form a curtain support, and a U-shaped rod having its ends secured to the lower front edge of each side and forming a support for the lower edge of the curtains disposed on said pair of rods.
